(57) CLAIM

The ornamental design for hand stamp handle, as shown and described.

DESCRIPTION

FIG. 1 is a perspective view of a hand stamp handle showing my new design;

FIG. 2 is a front elevation thereof;

FIG. 3 is a rear elevation thereof;

FIG. 4 is a left side elevation thereof; and,

FIG. 5 is a top plan view thereof.

The broken line showing a hand stamp base is for illustrative purposes only and forms no part of the claimed design.
